METHOD OF CRACKING OIL

Harold Sydnor, Elizabeth, N. J., assignor to
Standard Oil Development Company, a corpora-
tion of Delaware

Application March 20, 1931, Serial No. 524,067

1 Claim. (CL 196—51)

This invention relates to improvements in the operation of cracking equipment of the tube and tank type in which the flow of oil in the tank or digesting drum is from the top to the bottom. This method of operation is covered by my pending patent application Serial No. 412,193 filed December 6, 1929.

An object of the present invention is to provide for the control of temperature in the digesting drum, the reduction of coke formation in it, and the maintenance of the drum release line in a clean condition.

Another object of the invention is to provide a plurality of cracking circuits preferably heated by a common source of heat and both discharging into the upper portion of the digesting drum. Stocks of diverse character are to be heated under different conditions in the various circuits.

Referring to the drawing, which is a side elevation, partly in section, showing a preferred form of equipment, reference numeral 1 indicates a line through which the oil to be cracked, preferably crude petroleum oil, is fed into the heat exchange system. This comprises closed coils 2 and 3 arranged respectively in the upper parts of fractionating towers 4 and 5, and a tar heat exchanger 6. The oil so preheated is passed into the intermediate portion of tower 4 where it comes into direct contact with the reflux formed in the upper part of the tower.

The amount of heat acquired by the oil in passing through the heat exchange equipment is sufficient to vaporize the gasoline and naphtha contained in it. The conditions in tower 4 are so controlled that the gasoline passes overhead through a line 7 to cooling coil 8 and suitable storage not shown, while the heavy naphtha is withdrawn through a line 9 into an accumulator 10.

The cracking furnace 11 contains two tube circuits 12 and 13. The second of these is arranged in the hottest portion of the furnace adjacent the burners 14. The first circuit 12 is arranged in the cooler part of the furnace.

Circuit 12 is supplied with gas oil from tower 5. This gas oil is withdrawn from the bottom of tower 5 by line 15 through pumps 16 and thence into the inlet of circuit 12. Heavy naphtha is supplied to circuit 13 through line 17, pump 18, inter-condenser 19 and line 20.

The circuits 12 and 13 discharge respectively through lines 22 and 21 into a common line 23 opening into the upper part of the digesting drum 24. The release line 25 from this drum enters it at a point rather close to its bottom. A

pressure control valve 26 is installed in line 25. A separator 27 receives the oil discharged through line 25. Vapors are discharged from the separator through a line 28 into indirect heat exchange with the oil passing through inter-condenser 19 and thence into the intermediate portion of tower 5. This tower as well as tower 4 is provided with suitable fractionating means such as bellcap plates 29. Oil may be by-passed if desired from tower 4 to tower 5 through line 10. In this line there is a control valve 31.

Cracking conditions in the drum 24 are controlled according to this invention, in two ways: First by adjusting the relative amounts and heat content of the two streams of oil from the cracking circuits; and second by the introduction of relatively cool oil in the lower part of the drum. This latter is preferably accomplished by the drawing of the oil from the lower part of tower 4 through line 32 and pump 33, and injecting the oil into the drum at a point adjacent the inlet of the release line therefrom. It will be noted that the oil so supplied to the bottom of the drum is the crude oil reduced by flash vaporization in the tower 4. According to the present invention, this is an entirely practical and advantageous operation notwithstanding the fact that the oil contains relatively large amounts of heavy components. Such oil would be detrimental in a digesting drum operating on the principle of inlet at the bottom and outlet at the top. The heavy components of the introduced oil would tend to settle and accumulate in the drum where they would be converted into coke.

When operating with inlet at the top and outlet at the bottom the oil introduced does not have a chance to collect in the drum. It remains there-in long enough however to have a solvent effect on the heavy material which tends to form by polymerization of the oil in the drum. The introduced oil tends to flux these polymers and permits them to be readily carried off. In this way the amount of coke formed is greatly reduced. While some of the advantages of the invention may be obtained by introducing the relatively heavy oil into the lower part of the drum at any point, best results are obtained by injecting it as shown. The oil is in part forced into the outlet line and keeps the line clear of coke.

The method described above can be operated under a rather wide variety of conditions. The following is given by way of example.

Crude oil is passed into the system through line 1 and is stripped of its lighter fractions in tower 4 as described. The stripped oil from 55

5 tower 4 is passed through line 32 into drum 24 at a point adjacent release line 25. The temperature in circuit 12 is 900° to 925° F. and it is fed by gas oil from tower 5. The temperature in circuit 13 is 950° to 975° F. and it is fed from the heavy naphtha accumulator 10, which received its oil from the upper part of tower 4. It will be noted that this naphtha is straight-run. There are substantial advantages in cracking such naphtha at high temperature substantially in vapor phase as distinguished from recracking cracked naphtha.

10 The circuits and the digesting drum are held at a pressure of 700 to 800 lbs. per square inch. The temperature in the separator will be about 15 775° F.

15 The amount of oil to be introduced in the bottom of drum 24 will be determined by various conditions. In general it may be said that all 20 the reduced crude remaining after the removal of the gasoline and naphtha may be passed into the drum as described. However, if desired a part of this reduced crude may be withdrawn from tower 4 through line 34. The reduced crude 25 is thus subjected to high temperature conditions and the recovery of lower boiling components is thereby increased.

20 It will be understood that the conditions described above may be widely varied. In general 30 however it is preferred to have the drum operate substantially in vapor phase by maintaining the height of the liquid at the same height as the outlet pipe 25. In the cracking circuits the gas oil will usually be mostly in liquid phase and the heavy naphtha at least partly in vapor phase.

5 By the arrangement described it is possible to obtain a gasoline which has good anti-knock properties directly from crude oil, that is, the system is self-contained providing both for the stripping of the crude oil to yield a straight-run naphtha fraction for cracking and also for the cracking of this fraction and of other portions of the crude.

10 Various changes and alternative arrangements may be made within the scope of the appended 15 claim in which it is my intention to claim all novelty inherent in the invention as broadly as the prior art permits.

I claim:

15 Process of cracking oil comprising reducing a crude oil by flash vaporization to obtain a reduced crude oil, collecting a heavy naphtha and a light naphtha distillate substantially free from cracked products from such crude oil, heating the heavy naphtha to a cracking temperature 20 under pressure in an elongated narrow heating zone and introducing it into the upper part of an enlarged vertical digestion zone, heating gas oil to a cracking temperature lower than the above mentioned cracking temperature under 25 pressure in a separate elongated narrow heating zone and introducing it into the upper part of said enlarged vertical digestion zone, passing the reduced crude oil from which naphtha has been removed into the lower part of such zone in 30 hot state as obtained from the reducing operation, removing oil and vapor together from the lower path of the digestion zone, and separating gasoline from the removed product.

HAROLD SYDNOR.
